UNITED STATES PATENT OFFICE.

TONY BOGI, OF NANTY GLO, PENNSYLVANIA.

DUPLEX LIGHTING SYSTEM.

1,358,278.

Specification of Letters Patent.

Patented Nov. 9, 1920.

Application filed May 24, 1920. Serial No. 383,940.

To all whom it may concern:

Be it known that I, TONY BOGI, a citizen of the United States, residing at Nanty Glo, in the county of Cambria and State of Pennsylvania, have invented certain new and useful Improvements in Duplex Lighting Systems, of which the following is a specification, reference being had to the accompanying drawings.

10 This invention relates to duplex lighting systems and more particularly to duplex systems for use on head-gear such as worn by miners and persons required to work in dark places.

15 With the present form of acetylene lamps used by miners, should the gas become exhausted or the lamp damaged, there is no means to provide light for the miner, thus requiring the miner to leave his work and have the lamp repaired or replaced.

20 It is therefore an object of the invention to provide means for illuminating purposes that can be readily put into operation should the gas lamp be rendered useless.

25 Another object of the invention is to provide a duplex lighting system whereby the mechanism of one of the illuminating means provides a support for the other illuminating means.

30 Another object of the invention is to provide a lighting system of this character wherein the casing for one of the energizing means serves to hold the other illuminating means on a support or head-gear.

35 Another object of the invention is to provide a lamp forming one source of illumination and a second lighting system forming a second source of illumination, the casing of the lamp and reflector therefore forming 40 part of the circuit of the second mentioned illuminating means.

45 A still further object of the invention is to provide a lighting system using electrical energy and capable of being incorporated in various forms of lamps to be used instead of or when the lamps are not in use.

With these and other objects in view, the invention consists in the improved construction and arrangement of parts to be herein- 50 after more particularly described, fully claimed and illustrated in the accompanying drawings, in which:

Figure 1 is a side elevation of an acetylene gas lamp with the invention applied;

55 Fig. 2 is a horizontal sectional view;

Fig. 3 is a fragmentary perspective view

of a head-gear showing the construction of the support, and

Fig. 4 is a sectional view of the battery casing showing the contact means.

Referring to the drawings, A designates a lamp preferably of the acetylene type, and B the reflector therefor. The lamp A includes a bracket C which extends rearwardly of the lamp and is intended to be supported on a head-gear D including a support E. The support is provided with a laterally extending slot 5 which penetrates one edge of the support, the mouth of the slot being restricted.

In order to provide illuminating means when the lamp is not in order or the gas thereof has become exhausted, I provide an illuminating means 5, comprising the lamp receiving portion 6 which is embedded in an opening 7 formed in the reflector B adjacent the illuminating means of the lamp. The member 6 is not insulated from the reflector, as the reflector is intended to serve as electrical conducting means for the member 6. The other portion of the socket member comprises a conduit 8 which is bifurcated at one end and pivotally connected to an arm 9 carried by the exterior portion of the lamp A. The end portion 10 of the conduit 8 is externally threaded and adapted to receive an insulating sleeve 11, the end portion 12 of the insulating sleeve including a collar adapted to engage the rear portion of the lamp receiving member 6.

Projecting from the lamp casing is an arm 13 to which a cylindrical body 14 is secured. The body and arm are constructed of metal. An opening 15 is formed in the cylindrical body 14 and is adapted to permit unobstructed movement of the finger piece 16 carried by a contact member 17 disposed within the cylindrical body 14. The cylindrical body 14 and the contact member 17 coöperate to provide a switch by means of which the current is controlled.

A casing 18, is secured to the bracket C rearwardly of the lamp A. This casing is composed of two pivotal connected sections provided with a fastener F so that the casing may be readily opened when desired. The end 19 of the casing is composed of insulating material and is intended to receive a pair of contact members 20. Energizing means such as a battery 21 is intended to be disposed within the casing 18 with the ter-

minals thereof in engagement with the contacts 20. Leading from the contacts exteriorly of the casing 18 is a pair of current conducting wires 22 and 23. The end portion 5 of the wire 22 is extended to the conduit member 8 and is passed through the bifurcated portion adjacent the pivotal connection of said conduit to the arm 9 and into said conduit. Insulating means 24 are disposed 10 around the ends of the wire 22 so as to prevent closing of the circuit through the conduit member 8. The end portion of said wire is provided with a spring 25 to the end of which a contact plate 26 is secured. The 15 uninsulated end of the wire 22 and the spring 25 together with the plate 26 are disposed within the insulating sleeve 11, with the plate 26 closely adjacent the lamp receiving member 6. The wire 23 is extended through 20 one end of the cylindrical body 14 and insulated from said body. The contact member 17 of the switch is intended to engage the end of the wire 23 to close the circuit when desired.

25 A lamp 27 is screwed into the lamp receiving member 6, with the end thereof in contact with the plate 26. When it is desired to energize the lamp 27, the switch contact 17 is moved toward the end of the wire 23. 30 This causes the closing of the circuit through the cylindrical body 14, arm 13, lamp casing A, reflector B and lamp receiving member 6. The other portion of the circuit being formed by the wire 22, spring 25, and plate 26 in 35 contact with the end of the lamp 27. It will thus be seen that the lamp casing A and reflector B are utilized in the circuit of the lamp 27 thereby eliminating unnecessary wire and rendering the device simple.

40 In applying the lamp to a support, such as the head-gear D, the bracket C is passed through the slot E and is prevented from disengagement therefrom by the restricted opening of the slot. The casing 18 is thereby 45 positioned between the support E and the head-gear D to prevent disengagement of the lamp from the support so that it thereby serves two purposes.

To properly position the socket member 50 6 with respect to the reflector B, a supporting member 28 is carried by the socket member 6 rearwardly of the reflector B, said member including an extension 29 adapted to engage the insulating sleeve 11. This 55 member may be made of metal and serve as an additional means for conducting electrical energy to the socket member 6.

An important feature of the invention is 60 that the casing of the lamp not only serves as a support for the second illuminating means, but also serves as means by which current is transmitted to the lamp of the second illuminating means. The second illuminating means also co-operates with the lamp by permitting the casing containing the energizing

means therefor to serve as a fastening or holding device to prevent disengagement of the lamp from the support on the head-gear. In addition to this the reflector of the lamp is utilized to provide a support for the socket 70 or lamp receiving member of the second illuminating means. Notwithstanding these important features, the invention is simple in construction and can be incorporated in various forms of lamps to be used either as a 75 separate lighting arrangement or when the lamp is out of order.

What is claimed is:—

1. A duplex lighting system comprising a lamp casing, a reflector carried by said casing, a source of illumination carried by the casing, a second source of illumination carried by the reflector, a means carried by the first mentioned casing for supplying energy to the second source of illumination, and means carried by the first mentioned casing for controlling a supply of energy to the second source of illumination. 85

2. In a duplex lighting system, the combination with a lamp casing and reflector, 90 said lamp providing one source of illumination, a second source of illumination carried by the reflector, a casing carried by said lamp casing, energizing means disposed within said casing, electrical conducting 95 members carried by said energizing means, a switch carried by said lamp casing, one of said conducting members being connected to the switch and insulated therefrom, the other conducting member being disposed in engagement within the second mentioned 100 source of illumination, said switch closing the circuit through the lamp casing reflector and lamp socket.

3. In a duplex lighting system, the combination with a support, a bracket on said support, a slot in said bracket, of a lamp casing including a bracket, a casing carried by said bracket, said bracket being disposed in the slot of the support, said support being disposed between the casing and the lamp, a source of illumination provided for said lamp, a second source of illumination carried by the casing, energizing means disposed within the said casing, means for conveying energy from said energizing means to the second source of illumination, and means carried by said casing for controlling the supply of energy to the second source of illumination. 110 115

4. In a duplex lighting system, the combination with a lamp casing including a reflector, a bracket carried by the lamp, of a lamp receiving member disposed in said reflector, a lamp in said member, a conduit member, an insulating sleeve connecting the lamp receiving member to the conduit, a casing carried by the bracket of the lamp, energizing means disposed within the said casing, wires leading from said means to the 120 125 130

- second mentioned lamp, one of said wires extending through the conduit and being insulated therefrom, yieldable contact means carried by the end of said wire for engagement with said lamp, the other wire being connected to the switch and insulated therefrom, said switch closing the circuit through the lamp casing reflector and lamp receiving member.
- 5 10 5. A duplex lighting system comprising a metal lamp casing and reflector, illuminating means projecting from the casing through the reflector, a socket member, one portion of said socket member being carried by the reflector in circuit therewith and arranged to receive a lamp, the other portion of said socket member forming a conduit and being insulated from the lamp receiving portion and pivotally connected to the lamp
- 15 casing, a switch carried by the lamp casing, 20 the body of said switch being in circuit with the lamp casing, energizing means carried by the lamp casing for energizing said lamp, current conducting wires connected to said energizing means, one of said wires being 25 insulated from and extended through said conduit, resilient contact means on the end of said wire within the insulated portion of the socket, the other wire being connected to and insulated from the body of said 30 switch, means in said switch for closing the circuit through the body of the switch, lamp casing reflector and lamp receiving member of the socket.

In testimony whereof I hereunto affix my 35 signature.

TONY BOGI.
